TOOL CABINET

Edward H. Simonsen, Elmwood Park, Ill., assignor to Simonsen Metal Products Company, Chicago, Ill., a corporation of Illinois

Application October 25, 1956, Serial No. 618,282

3 Claims. (Cl. 280—47.19)

This invention relates to cabinet structures and is more particularly concerned with improvements in a cabinet of the portable type which is adapted to house a plurality of mechanics' tools or other similar objects.

It is a general object of the invention to provide a portable tool cabinet which is particularly designed for use by aviation and automobile mechanics and others who have need for a substantial number of tools, spare parts, etc. while engaged in repair operations, or the like, and who desire to be able to readily move such equipment from one job location to another and to keep it assembled and ready for use so that it is not necessary for the user to search for a required tool or part at a bench or cabinet remote from the job.

It is a more specific object of the invention to provide a portable cabinet of substantial size which is capable of housing a substantial number of tools or similar objects in a readily accessible manner, which has a top arranged to provide work space thereon, and which may be readily moved from place to place.

It is another object of the invention to provide a work cabinet of the type described in which the top and bottom members are each formed from one piece of cast or drawn sheet metal and in which the body is formed from a single sheet of metal plate bent to provide a back and side walls, with the latter being connected at the top and bottom edges to integral flanges on the top and bottom members, and having a pair of door members arranged in the open face thereof.

It is another object of the invention to provide a cabinet structure of the type described in which the top of the cabinet is recessed to provide for the retention thereon of a substantial number of tools or parts when the cabinet is tilted in moving the same from place to place.

It is a further object of the invention to provide in a portable tool cabinet of the type described a unitary wheel assembly which comprises a one piece metal bracket and a pair of wheels having supporting shafts which are journaled in the ends of the bracket, with the assembled unit being adapted to be secured by suitable fastening members in the bottom rear portion of the cabinet.

These and other objects and advantages of the invention will be apparent from a consideration of the tool cabinet which is shown by way of illustration in the accompanying drawings wherein:

Figure 1 is a perspective view of a portable tool cabinet embodying the principal features of the invention;

Figure 2 is a front perspective view of the cabinet with the doors in the open position;

Figure 3 is a rear elevation of the cabinet;

Figure 4 is a vertical cross section taken on the line 4—4 of Figure 3;

Figure 5 is a horizontal cross section taken on the line 5—5 of Figure 4;

Figure 6 is a cross section taken on the line 6—6 of Figure 4 to an enlarged scale;

2

Figure 7 is a perspective view of the wheel assembly; and

Figure 8 is a perspective view of the unitary wheel assembly illustrating the manner of assembling the wheel with the supporting bracket.

Referring first to Figures 1 to 3, the cabinet 10 is preferably formed from sheet metal with a top member 11, a bottom member 12, and a body or side wall forming member 13. The top forming member 11 is drawn or stamped from a single sheet of metal plate material and provided with a depending peripheral flange 14 and a recessed central portion 15 which acts as a tray-like container for receiving tools or other articles loosely therein. The bottom forming member 12 is likewise drawn or stamped from a single sheet of metal plate and provided with an upstanding peripheral flange 16. The body forming member 13 is shaped to provide a back wall 17, oppositely disposed side walls 18 and 19, and flange-like front edge portions 20 and 21 which define the side edges of the open front 22 of the cabinet. The generally U-shaped body member 13 is secured between the top and bottom members 11 and 12 by welding or otherwise fastening the edges thereof to the flanges 14 and 16 of the top and bottom members 11 and 12, respectively. The front opening 22 of the cabinet is closed by a pair of cooperating door forming members 23 and 24 which are hinged at 25 and 26, respectively, to the body forming edge portions 20 and 21. A suitable latch and handle 27 with a locking arrangement is provided to retain the doors 23 and 24 in closed position when desired. One of the door members 23 is preferably provided on its inner surface with a removable frame arrangement 28 which provides a series of shelves 29 for receiving small tools. The other door member 24 is preferably lined with a peg board for receiving hangers for small tools, etc. The cabinet 10 is provided with one or more shelves. For the purpose of illustration, it is shown as having pairs of vertically spaced horizontally disposed shelf forming members 30, 31, and 32, 33. The two shelves of each pair are spaced relative to each other so as to provide for receiving therebetween a plurality of drawer members 34 which may be of varying width and which are provided on their front faces with drawer pulls 35. The shelf members 30, 31 and 32, 33 are located and supported on the side walls 18 and 19 by indented wall portions or punched tongue members 36 which are arranged in the side and back walls to properly space the shelves 30, 31 and 32, 33 so that they are level when the cabinet is in the upright horizontal position. Each of the shelves 30, 31 and 32, 33 is provided with depending flange sections 37 at the end edges and along the rear edge thereof which are received in the openings 38 formed by punching the tongues 36 in the walls, as shown in Figure 6. Each uppermost shelf is also provided with an upstanding flange 39 along the front edge which serves to retain the tools or other articles on the shelves and normally prevents the same from falling out of the cabinet. The openings 38 formed by punching the tongues 36 in the side walls 18 and 19 and back wall 17 provide ventilation for the cabinet and permit circulation of air throughout the interior thereof.

The cabinet is normally held in upright position by four supporting feet or leg members 41 which are arranged two at the front corners and two at the rear of the bottom member 12. The feet 41 are provided with flange portions 42 for attaching the same by welding to the bottom surface of the bottom member 12.

To enable the cabinet 10 to be readily moved from place to place, a wheel assembly 43 (Figures 3, 4, 5, 7 and 8) is provided which comprises an assembly bracket 44 and a pair of wheels 45, the latter being of conventional rubber tired construction. The wheel assembly

bracket 44 is preferably fabricated from a strip of metal plate which is bent to form a generally U-shaped member having a central or bight forming section 46 and two wheel housing side sections 47 forming the legs of the U. Each wheel housing 47 comprises oppositely disposed spaced parallel wall members 48 and 49 with the inside wall member 48 having one end integral with the center bracket section 46 and connected at the other end by a web portion 50 with the end of the outside wall member 49. The wall members 48 and 49 are provided with flanges 51 and 52 at the bottom having bolt receiving holes 53 and each of these wall members has a bearing 54 with the two bearings being aligned when the wall members 48 and 49 are in parallel relation to receive the shaft 55 on which the wheel 45 is mounted. In assembling the wheel 45 with the bracket housing 47, the outside wall member 49 is bent outwardly (Figure 8) sufficiently to permit insertion of the ends of the wheel shaft 55 in the bearing members 54 after which the outside wall member 49 is bent or sprung back into parallel relation with the inside wall member 48 and the assembly is installed as a unit in the cabinet structure. The center section 46 of the bracket 44 is provided on its lower edge with a flange 46'.

The back wall 17 of the cabinet 10 is slotted at 56 adjacent the bottom corners to receive the wheel housings 47 and the bottom wall 12 of the cabinet is cut away or slotted at 57 to accommodate the wheels 45. Each pair of slots 56, 57 is, of course, aligned and the wheel assembly 43 is inserted from the outside of the back wall 17 and bolted into position by the bolts 58 which extend through the bolt holes 53 in the flanges 51 and 52 of each housing 47. The bottom edge of the back wall 17 rests on the flange 46' and the assembly 44 is located so that the wheels 45 are free of the supporting surface when the cabinet is in upright position and resting on the feet 41.

A handle in the form of an inverted U-shaped bar or pipe member 60 is attached to the back wall 17 of the cabinet 10 with the bight portion 61 forming an upstanding rearwardly curved hand gripping portion and the legs 62 depending along the back wall and secured thereto by brackets 63 which are welded or otherwise secured to the outside surface of the back wall member 17. The legs 62 of the handle members 60 are preferably provided with a series of axially spaced holes and adjustably secured to the brackets 63 by bolts 64 extending through the holes when the handle is at the desired height. The handle member 60, of course, permits the user to manually tilt the cabinet 10 in a rearward direction sufficiently to shift the support thereof to the wheels 45 so that it may be readily wheeled about.

An additional tool guard 65, of generally U-shaped configuration, may be provided which is attached by bolts, screws 66 or otherwise, to the flanged margins of the top forming member 11 or to the upper portions of the side or back walls to confine any tools or other items which are placed thereon to the table forming surface provided by the top member 11.

The cabinet 10 is particularly adapted to house tools and small parts which are generally used by repair mechanics and other similar workmen. The recess 15 in the top member 11 provides a convenient work surface which the user may have available close to the job on which he is working. His tools and equipment for use on the job are assembled by means of the cabinet in a convenient location and may be readily moved to any desired place as the user moves about. The cabinet 10 may, of course, be used for other purposes such as the display of merchandise or the like.

While specific materials and particular details of construction have been referred to in describing the illustrated form of the device, it will be understood that other materials and other details of construction may be resorted to within the spirit of the invention.

I claim:

1. In an upright cabinet structure formed from metal plate members which are bent and connected together to provide a top, a bottom, a back wall and adjoining side walls, a wheel assembly for said cabinet comprising a one piece bracket forming member of generally U-shape which is bent to provide a pair of oppositely disposed wheel housings and a connecting web member, a pair of wheels supported on axles which are journaled in said housings in aligned relation, said cabinet bottom and back wall having aligned apertures at their adjoining edges which are spaced inwardly of the side walls and said wheel assembly being secured on said cabinet with the wheel housings extending through the apertures in said cabinet bottom and back wall and enclosed within the cabinet.

2. A sheet metal tool cabinet comprising top and bottom members, an upright back and side wall forming body member, said top and bottom members being connected to the corresponding edges of said upright body member along the back and the two adjoining side edges, said bottom member and the back of said wall forming member having aligned apertures at the bottom back corners of the cabinet which extend a predetermined distance into the back and bottom walls adjacent the inner faces of the side walls, and a unitary wheel assembly secured along the bottom back edge of the cabinet, said wheel assembly comprising a one piece sheet metal frame bent to form spaced rearwardly opening U-shaped sections connected by a back wall forming web and a pair of wheels arranged on axially aligned wheel supporting shafts mounted in said U-shaped sections, said U-shaped sections being seated in said apertures so that the wheels project from the rear and bottom walls of the cabinet.

3. In an upright cabinet structure formed from metal plate members which are connected together to provide a top, a bottom, a back wall and adjoining side walls, said bottom and back walls having transversely aligned openings in the bottom and back corners of the cabinet adjacent the inner faces of the side walls, and a unitary wheel assembly secured along the bottom back edge of the cabinet, said wheel assembly comprising a sheet metal frame which has its end portion shaped to provide a pair of wheel housings and a connecting web member, said wheel housings comprising spaced rearwardly and downwardly opening U-shaped sections with the inner edges connected to opposite ends of said web member and forming rectangular wheel enclosures with adjacent bottom and rear faces open and unobstructed, said U-shaped sections having aligned bearing formations for receiving wheel supporting shafts, wheels carried on said shafts of a size to project through the open bottom and rear faces between the corresponding edges of the U-shaped sections and said U-shaped sections being seated in said wall openings so that the wheels project from the bottom and back walls of the cabinet.
